ELECTRICAL SWITCH

Avery L. Salter, Johnston, S. C.

Application July 15, 1940, Serial No. 345,622

21 Claims. (Cl. 200—116)

My invention relates to electric switches for lines and transformers and the like.

An important object of the invention is to provide a switch of the above mentioned character which will automatically open the circuit upon a short circuit as well as upon an overload.

A further object of the invention is to provide a switch of the above mentioned character embodying a thermo-trip element which will open the switch upon a short circuit and also upon an overload.

A further object of the invention is to provide a switch of the above mentioned character having a latch device which is released by the thermo-trip element and which latch device is automatically locked when the switch drops to the lowered position, whereby the switch may be restored to its normal operative position by the use of a pole.

A further object of the invention is to provide a switch of the above mentioned character, the resetting of which will not necessitate the operator climbing the usual pole and passing between high tension or dangerous wires.

A further object of the invention is to provide a switch of the above mentioned character which is of simplified construction and which may be manufactured cheaply.

A further object of the invention is to provide a switch of the above mentioned character which is operated by a thermo-trip element without the use of a thermo-fusible element, whereby the line may be better coordinated.

A further object of the invention is to provide a thermo-trip element in the form of a bimetal strip that controls the capacity of the current allowed to pass over the line and which may be built for different amperage capacity suitable for the load which will enable the line to be better coordinated.

A further object of the invention is to provide a switch of the above mentioned character which will operate properly on lines and transformers of a minimum voltage or load capacity.

A further object of the invention is to provide a switch of the above mentioned character which is also adapted for use upon high capacity lines in connection with suitable means for preventing arcing, when opening the circuit.

A further object of the invention is to provide automatic means for preventing arcing, when the circuit is opened by the switch, upon a short circuit or overload.

A further object of the invention is to provide means for enclosing or housing the operating

parts of the switch, when it is closed, thus protecting the same from the elements and also serving as a safety factor.

A further object of the invention is to provide a housing for the switch which will not interfere with the proper operation of the switch.

Other objects and advantages of the invention will be apparent during the course of the following description.

10 In the accompanying drawings forming a part of this application and in which like numerals are employed to designate like parts throughout the same:

Figure 1 is a side elevation of a switch embodying my invention, showing the same in the raised closed position,

Figure 2 is a similar view, showing the latch device released and the pivoted support turned with respect to the body of the switch, which is somewhat lowered,

Figure 3 is a similar view, showing the body of the switch dropped to the lowered vertical position and the latch device reset,

Figure 4 is a side elevation of the switch device, showing the latch in the locked position,

Figure 5 is a longitudinal section taken on line 5—5 of Figure 4,

Figure 6 is a similar view taken on line 6—6 of Figure 5,

30 Figure 7 is a plan view of the upper contact and associated elements, parts omitted,

Figure 8 is a horizontal section taken on line 8—8 of Figure 5,

Figure 9 is a similar view taken on line 9—9 of Figure 5,

Figure 10 is a similar view taken on line 10—10 of Figure 5,

Figure 11 is an enlarged vertical section taken on line 11—11 of Figure 5,

40 Figure 12 is a side elevation of a switch embodying a modified form of my invention, showing the same in the raised closed position,

Figure 13 is a similar view, showing the latch device released and the pivoted support turned with respect to the body portion of the switch, which is somewhat lowered, the housing being in vertical section,

Figure 14 is a similar view, showing the body portion of the switch dropped to the lowered vertical position and the latch device reset,

50 Figure 15 is a front elevation, showing the switch in the raised closed position and the housing closed,

Figure 16 is a similar view of the housing shown in vertical section,

Figure 17 is a vertical section taken on line 17-17 of Figure 16, parts omitted.

Figure 18 is a horizontal section taken on line 18-18 of Figure 12.

Figure 19 is a similar view taken on line 19-19 of Figure 12.

Figure 20 is a similar view taken on line 20-20 of Figure 12, and.

Figure 21 is a transverse vertical section taken on line 21-21 of Figure 12.

In the drawings, wherein for the purpose of illustration are shown preferred embodiments of my invention, attention being called first to Figures 1 to 11 inclusive, the numeral 15 designates an inclined insulator, suitably mounted upon a pole by a bracket 16 or the like. Mounted upon the upper end of the insulator 15 is a terminal 17, formed of metal, while a terminal 18 formed of metal is mounted upon the lower end of the insulator. The line 19 is connected with the upper terminal 17 and the load 20 with the lower terminal.

Suitably secured to the upper terminal 17 is a resilient stationary metal contact 21, which is forked for providing spaced arms 22 having recesses 23. Attached to the lower terminal 18 is a metal bracket 24, which is forked for providing spaced arms 25 carrying hooked ends or knuckles 26.

The numeral 27 designates the body portion of the switch, which is formed of insulating material. The body portion 27 has a reduced upper extension 28 to which is secured by screws 29 or the like a metal cap 30. This metal cap has formed integral therewith a forwardly projecting head 31, carrying a horizontal transverse metal pin 32. The cap 30 has a ring 33, preferably formed integral therewith and this ring is arranged opposite of and remote from the head 31. The pin 32 is adapted for contact with the arms 22. At its lower end, the body portion 27 is provided with a reduced extension 34, having a metal sleeve 35, securely attached thereto by means of a bolt or pin 36 or any other suitable means. The metal sleeve 35 has a depending shank 37 carrying a forwardly facing up-turned hook 38.

The numeral 39 designates a supporting yoke, having a forwardly facing up-turned hook 40. The yoke 39 has sides 41, which are provided at their lower ends and adjacent to their rear edges with trunnions or pivots 42, integral therewith. These trunnions or pivots 42 are pivotally mounted within the hooks or bearings 28. The upper ends of the sides 41 are apertured, as shown at 43, to pivotally receive pivot elements or trunnions 44, rigidly secured to the sleeve 35. Particular attention is called to the fact that the contact pin 32 is disposed off-center or to one side of the pivots 44 and 42 with respect to the longitudinal axis of the body portion 27. The contact pin 32 is normally held within the recesses 23 and the yielding or resilient contact 21 exerts a downward force upon the pin 32 and body portion 27, tending to turn the yoke 39 upon its pivots 42.

The hook 38 is arranged to engage with the sleeve 45 of the yoke 39 and thereby prevent the sleeve 35 from turning clockwise, Figure 5, with respect to the yoke. A latch device is provided which normally prevents the sleeve 35 from turning counter-clockwise with respect to the yoke 39, Figure 5. This latch device comprises a lever 46, which is generally vertical and extends through an opening 47, and projects down-

wardly beyond the sleeve 35. The lever 46 is pivotally mounted upon the bolt 36. The lever 46 swings in a vertical plane at a right angle to the swinging movement of the body portion upon the pivots 44. The lower portion of the lever 46 slidably engages with a part of the shank 37 and the lever is provided at its lower end with a lateral extension or tooth 48, extending longitudinally of the pivots 44 or at a right angle to the swinging movement of the yoke 39. The tooth 48 has a forward inclined face 49 and a rear inclined face 50. The rear inclined face 50 is adapted to engage with a forward inclined face 51 of a stationary lug 52, formed integral with one side 41 while the inclined face 49 is adapted to engage with the rear inclined face 53. It is obvious that when the tooth 48 is held between the lug 52 and the shank 37 and the hook 38 engages the web 45, that the sleeve 35 cannot turn in either direction with respect to the yoke. A slight retractile coil spring 54 is connected with the upper portion of the lever 46, and serves to swing the upper end of the lever to the left, Figure 6, and its lower end to the right, so that tooth 48 will engage behind lug 52.

The numeral 55 designates a bimetal thermo-trip element, formed of two metals having different coefficients of expansion. The ends of this U-shaped thermo-trip element are detachably clamped to stationary brackets 56, mounted upon the insulated body portion 27. At the closed end of the U-shaped thermo-trip element, and beneath the same, a stop element or strip 57 is provided, which is rigidly mounted upon the thermo-trip element and thoroughly electrically insulated therefrom, the strips 58 being insulated mica strips. The lever 46 is provided at its upper end with a lateral extension or dog 59, rigidly secured thereto, and operating beneath the U-shaped thermo-trip element 55 and arranged inwardly of the stop element 57, Figure 10.

The numeral 60 designates a wire, passing through an opening 61, and electrically connected with the sleeve 30 and with one bracket 56 and one arm of the U-shaped thermo-trip element 55. The other bracket 56 in electrical connection with the other arm of the thermo-trip element 55 is electrically connected with a wire 62, electrically connected with the bolt 36 and hence electrically connected with the sleeve 35 and yoke 39.

The operation of the switch is as follows: In Figure 1, the switch is shown in the circuit closing position. The current from the line 19 passes through contact 21, pin 32, wire 60, through U-shaped thermo-trip element 55, through wire 62, through sleeve 35, yoke 39 and bracket 24 to the load 20. The resilient contact 21 is exerting a downward force upon the pin 32 in a direction longitudinally of the body portion 27, and since the trunnions 42 are disposed off-center or laterally of the pin 32, the yoke 39 will turn clockwise, Figure 1, upon its trunnions 42, if not held against such turning movement. The slight turning of the yoke 39 clockwise upon its trunnions 42 causes the inclined face 51 to act upon the inclined face 53, which will tend to turn the lever 46 upon its pivot 36 so that the dog 59 will engage the stop element 57. The lever 46 is therefore normally held against any considerable turning movement upon its pivot 36 so that inclined faces 51 and 53 cannot disengage. Whenever a short circuit

or overload occurs, the current heats the thermo-trip element 55 beyond the normal temperature and this thermo-trip element bends upwardly whereby the stop element 57 is elevated out of the path of travel of the forward end of the dog 59. The downward pressure of the resilient contact 21 now acting upon the pin 32 is transmitted to the body portion 27, and the yoke 39 will turn its trunnions 42 and the sleeve 35 will turn upon its pivots 44, so that the yoke will break with respect to the body portion or turn clockwise with relation thereto, Figure 2, whereby the body portion 27 is lowered. This will bring the pin 32 to an elevation well beneath the arms 23, while the inclined face 49 is in advance of the inclined face 53. The body portion now drops to the lowered vertical position, Figure 3, and the body portion and yoke 39 assume a position at a straight angle with relation to each other and the inclined face 49 will ride over the inclined face 53, since the lever 46 is free to turn upon its pivot 36 except for the opposition of the slight spring 54, which is now overcome. The tooth 48 again locks behind the lug 52. The circuit being open, the thermo-trip element 55 cools and straightens out so that the stop element 57 is again in advance of the free end of the dog 59, and the yoke 39 is again locked against turning movement in both directions with respect to the sleeve 35. The operator may stand on the ground and insert a pole in the ring 33 and swing the body portion 27 to the raised position so that the pin 32 will again engage beneath the contact arms 22 and enter the recess 23 whereby the circuit is again closed through the switch, as explained. When the switch is used on a line or transformer of a low minimum voltage it is unnecessary to use any devices for preventing arcing. However, when the switch is used upon lines or transformers of high capacity suitable means will be employed to prevent arcing at the instant that the circuit is opened. The thermo-trip element 55 may have any selected rated amperage capacity and therefore the thermo-trip element will bend upwardly to release the dog 59, should the flow of current through the same be increased above its selected rated amperage capacity, as caused by a permanent overload or a short circuit, whereby the switch will automatically open the circuit. My switch will open the circuit upon a short circuit as well as an overload and since it does not provide a thermo-fusible element no such element need be replaced before again closing the switch. The latch device automatically relocks itself when the body portion of the switch reaches the lowermost vertical position and it is only necessary for the operator to insert a pole or the like in the ring 33 and swing the body portion to the uppermost position. This saves time in reclosing the switch and eliminates the danger of a service man having to climb between dangerous lines. The thermo-trip element that controls the capacity of the current allowed to pass over the line can be built of different or any desired amperage capacity suitable for the load. This will enable power companies to coordinate a line much better than with a fuse, for once a fuse link has been heated and not blown, the capacity of the use is weakened, but the heating of the bimetal thermo-trip element does not weaken the same below its rated capacity.

Attention is now called to the second form of the invention shown in Figures 12 to 21 inclusive. In this second form of the invention the

major portion of the construction is identical with that shown and described in connection with the first form of the invention.

In these figures, 12 to 21 inclusive, the numeral 63 designates a housing formed of electrical insulating material and which is also waterproof. This housing is vertical and includes a back 64, sides 65, top 66, while its front and bottom are open. The housing is to be rigidly mounted upon a pole or the like. The front of the housing is covered or closed by a door 67, formed of insulating material which should also be waterproof and having an eye 67'.

The top 66 of the housing may preferably be slightly inclined to shed water and arranged beneath this top, within the housing, are horizontal blocks 68, of insulating material and which are preferably formed integral with the top. The rear ends of these blocks are spaced from the back 64 to provide a recess 69 to receive a transverse electrical conductor-bar 70 held in place by a screw 71. This electrical conductor-bar is provided at its opposite ends with screw-threaded sockets 72, for connection with a terminal screw 73 for connection with the line 74. The terminal screw 73 may thus be connected with either end of the electrical conductor-bar 70. The blocks 68 have their inner faces spaced and these inner faces are vertical and are longitudinally inclined in a horizontal direction and diverge forwardly providing a forwardly diverging chamber 75. This forwardly diverging chamber receives therein a pair of resilient contacts 76, which are longitudinally curved and have their free ends resting upon the inner faces of the blocks 68 and their rear ends rigidly mounted upon and in electrical connection with the electrical conductor-bar 70. The blocks 68 terminate inwardly of the front edges of the sides 65 and form stops for the upper end of the door 67 so that this door is flush with the front edges of the sides when the door is closed.

Arranged immediately below the resilient contacts 76 is an arc extinguishing means, comprising a pair of reciprocatory plates 77, having inner edges 78, tapered or rounded at their forward ends while the rear portions of these edges are straight so that they are adapted to engage and cover the resilient contacts 76. The plates 77 are formed of electrical insulating material and are mounted to slide horizontally in a transverse direction in stationary guides 79 and are urged inwardly by bow-springs 80, as shown. These insulating plates 77 are arranged immediately beneath the resilient contacts 76, as clearly shown in Figure 13.

Arranged within the upper portion of the housing are downwardly operating leaf-springs 81, having raised sockets 82. The forward ends of these leaf-springs are preferably secured to the forward ends of the blocks 68, as shown at 83, and the rear ends of the leaf-springs are preferably connected with retractile coil springs 84, the lower ends of which are attached to the sides 65. If desired, the leaf-springs 81 may be made sufficiently stiff and the coil springs 84 omitted. These leaf-springs 81 are spaced and are arranged near the sides 65, as shown.

Arranged within the lower end of the housing 63 are socket-bearings 85, facing upwardly and preferably inclined forwardly. These socket-bearings are rigidly mounted upon the sides 65 by screws 86 or the like. These socket-bearings are formed of metal and are in electrical engagement with a metal U-shaped electrical con-

ductor-bar 87, Figure 20, and this bar is secured to the back 64 by a screw 88 or the like engaging within a sleeve 88' integral with the conductor-bar 87. The sides of this U-shaped bar are provided with screw-threaded sockets 89 adapted to receive a terminal screw 90, for connection with the load 91. It is thus apparent that the load may be electrically connected with either side of the U-shaped electrical conductor-bar and hence placed in electrical connection with the socket-bearings.

In the second form of the invention the same insulated body portion 27 is used, having the reduced ends 28 and 34. The body portion is rigidly held within sleeves or clamps 92 and 93, which are in turn rigidly mounted upon the inner face of the door 67. The reduced portion 28 carries a metallic cap 94, corresponding to the cap 30 in the first form of the invention. This metallic cap carries an L-shaped contact blade 95, preferably integral therewith. The vertical arm 96 of the contact blade is adapted to pass between the resilient contacts 76 and to have electrical engagement therewith and the vertical arm is provided at its top with an extension 97, tapering upwardly, to gradually reduce the contact area between the contact blade and the resilient contacts 76, when the contact blade drops. The contact blade is provided with a transverse horizontal pin 98, rigidly secured thereto, and this pin is arranged to engage the leaf-springs 81 and to enter the upwardly bulging sockets 82.

The same sleeve 35 is mounted upon the lower reduced end 34 and carries the depending shank 37 having the forwardly facing up-turned hook 38. The same supporting yoke 39 is used which pivotally supports the sleeve 35. The trunnions 42 of the yoke 39 are pivotally mounted within the socket-bearings 85. The same means are provided for holding the body portion 27 from turning upon the pivots 44 of the yoke 39, including the lever 46, jaw 49, and jaw 52. The same means is provided to hold the lever 46 against movement which would release the yoke 39, including the dog 59, stop element 57, and bimetal thermo-trip element 55. The same spring 54 is used. These elements are all identical with the corresponding elements shown and described in connection with the first form of the invention and it is thought to be unnecessary to again describe them in detail. The operation is identical. The same wire 60 is employed to electrically connect one arm of the thermo-trip element 55 with the sleeve 94 and the same wire 62 is employed to connect the other arm of the thermo-trip element 55 with the sleeve 35.

The operation of the second form of the invention is as follows:

The lever 46 and associated elements and the hook 38 serve to lock the body portion 27 against turning movement with respect to the yoke 39, in both directions, upon the pivots 44. Under these conditions the door 67 is swung to the upper substantially vertical closed position, the yoke 39 turning upon the trunnions 42. The pins 98 will engage the leaf-springs 81 which will yield and the pins will then enter the sockets 82 and be held therein. Attention is called to the fact that the pins 98 are arranged off-center or to one side of the pivots 44 and 42, Figure 12. As long as the yoke remains locked to the sleeve 35 by the action of the lever 46, the body portion 27 and door 67 cannot swing outwardly and downwardly since the pins 98 are

held within the sockets 82, the springs 81 exerting a downward pressure upon the pins. Upon a short circuit or overload, the thermo-trip element 55 will bend upwardly, and the dog 59 will clear the stop element 57, as described in connection with the first form of the invention. The body portion 27 will then swing counterclockwise with respect to the yoke 39, and the body portion 27 and door 67 will drop, as shown in Figure 13. The contact blade will be withdrawn from engagement with the resilient contacts 76, and the arcing will be extinguished by the closing of the plates 77, which occurs instantaneously upon the withdrawal of the contact blade 95 from beneath the same. The body portion 27 and door 67 will now swing outwardly and downwardly to assume the lowered vertical position, Figure 14, and the yoke 39 will again become locked to the sleeve 35. The body portion 27 and door 67 may again be returned to the raised closed position by the insertion of a pole into the eye 67', whereby the switch will again close the circuit.

While I have shown the circuit as being closed, in the first form of the invention through the springs 21 and pins 32, yet I contemplate employing the contact blade 95 and resilient contacts 76 in connection with the first form of the invention.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described my invention, what I claim is:

1. In a switch of the character described, a body portion, a contact element mounted upon the body portion, a resilient contact to engage the contact element and exert a downward force thereon longitudinally of the body portion, a support, a member pivotally mounted upon the support and pivotally connected with the body portion, a releasable latch device to hold the body portion for turning upon its pivotal connection with the member, means to normally hold the latch device against releasing action and to release the latching device for releasing action upon a short circuit or overload, said means including a bimetal thermostatic element adapted to move when heated without fusing, and means for permanently electrically connecting one end of the thermostatic element with the contact element and permanently electrically connecting the other end of said thermostatic element with the member so that the current passes through the thermostatic element to heat the same and cause its movement.

2. In a switch of the character described, a body portion, a contact element mounted upon the body portion and adapted to be engaged by a resilient contact which exerts a downward force thereon longitudinally of the body portion, a member pivotally mounted upon the body portion and adapted to be pivotally supported, a releasable latch device to hold the body portion from turning upon its pivotal connection with the member, said latch device including a movable part, a bimetal thermostatic element having a stop element normally arranged in the path of travel of said movable part, the thermostatic element moving in one direction when heated be-

yond a selected temperature without fusing and moving the stop element out of the path of travel of said part, and means for permanently electrically connecting one end of the thermostatic element with the contact element and permanently electrically connecting the opposite end of said bimetal thermostatic element with said member so that the current passes through the thermostatic element to heat the same.

3. In a switch of the character described, a body portion, a contact element mounted upon the body portion, a resilient contact to engage the contact element and exert a force thereon longitudinally of the body portion, a support, a member pivotally mounted upon the support and pivotally connected with the body portion, a lever pivotally mounted upon the body portion, a stop element mounted upon said member to engage with the lever, a bimetal thermo-trip element mounted upon the body portion and carrying a stop element to engage with said lever, and means electrically connecting the thermo-trip element with the contact element and said member.

4. In a switch of the character described, a body portion, a contact element mounted upon the body portion, a resilient contact to engage the contact element and exert a force thereon longitudinally of the body portion, a support, a member pivotally mounted upon the support and pivotally connected with the body portion, a lever pivotally mounted upon the body portion to swing in a plane at substantially a right angle to the plane of movement of the member with relation to the body portion, said lever being provided with an inclined face, a stop element carried by the member and arranged to engage the inclined face, a bimetal thermo-trip element mounted upon the body portion and having a stop element arranged in the path of travel of the lever, and means to electrically connect the thermo-trip element with the contact element and said member.

5. In a switch of the character described, a body portion, a contact element mounted upon the body portion, a resilient contact to engage the contact element, a support, a member pivotally mounted upon the support and pivotally connected with the body portion, a lever pivotally mounted upon the body portion to swing in a plane at substantially a right angle to the plane of movement of the member with relation to the body portion, said lever having a part provided with oppositely arranged beveled faces, a stop element mounted upon the member to engage with the beveled faces, a thermo-trip element which will bend when overheated mounted upon the body portion and having a stop element normally arranged in the path of travel of the lever, and means to electrically connect the thermo-trip element with the contact element and said member.

6. In a switch of the character described, a body portion, a contact element mounted upon the upper end of the body portion, a resilient contact to engage the contact element and exert a downward force thereon longitudinally of the body portion, a support, a member pivotally mounted upon the support and pivotally connected with the lower end of the body portion at a point which is off-center with respect to the contact element, a lever extending longitudinally of the body portion and pivotally mounted upon the body portion to swing in a plane at substantially a right angle to the plane of movement of the member with relation to the body portion,

5 said lever being provided near its lower end with oppositely arranged beveled faces, a stop element mounted upon said member and projecting into the path of travel of said beveled faces, a spring to move the lever in one direction so that the beveled faces are disposed in alignment with the stop element, a thermo-trip element which will bend when overheated mounted upon the body portion and having a stop element normally arranged in the path of travel of the upper portion of the lever, and means to electrically connect the thermo-trip element with the contact element and said member.

7. In a switch of the character described, an insulating body portion, a cap mounted upon the upper end of the body portion and provided with a contact element, a resilient contact to engage the contact element and exert a downward force thereon longitudinally of the body portion, a second cap mounted upon the lower end of the body portion and having a shank, a support, a yoke pivotally mounted upon the support and pivotally connected with the second cap at a point off-center with respect to the contact element, said shank having a part to engage with a part of the yoke to prevent the second cap from turning in one direction with relation to the yoke, means to prevent the second cap from turning in an opposite direction with relation to the yoke including a lever extending longitudinally of the body portion and pivotally mounted thereon to swing in a plane at substantially a right angle to the plane of movement of the yoke with respect to the second cap, said lever being provided near its lower end with a pair of oppositely arranged beveled faces, a stop element mounted upon the yoke and having a pair of oppositely arranged beveled faces arranged in the path of travel of the first named beveled faces when the lever is in the holding position, a spring to move the lever toward the holding position, a thermo-trip element adapted to bend when overheated mounted upon the body portion and having a stop element arranged in the path of travel of the upper end of the lever, and means to electrically connect the thermo-trip element with the first and second named caps.

8. In a switch of the character described, a supporting member mounted to swing, a body portion pivotally mounted upon the swinging supporting member, means for holding the body portion against swinging movement with relation to the supporting member, said means including a pivoted lever mounted to move in a plane at substantially a right angle to the plane of movement of the supporting member with relation to the body portion, and electrical means mounted upon the body portion for controlling the movement of said lever.

9. In a switch of the character described, a member mounted to swing, a body portion pivotally mounted upon the member, an element carried by the body portion and engaging said member to hold the body portion against turning movement in one direction with relation to the member, means for holding the body portion against turning movement in an opposite direction with relation to said member, said means including a pivoted lever mounted to move in a plane at substantially a right angle to the plane of movement of the supporting member with relation to the body portion, an electrical means mounted upon the body portion for controlling the movement of said lever.

75 10. In a switch of the character described, a

body portion, a contact element mounted upon the body portion, a resilient element to move the body portion in one direction, a support, a member pivotally mounted upon the support and pivotally connected with the body portion, a releasable latch device to normally hold the body portion from turning upon its pivot with relation to the member, a bimetal thermostatic element for controlling the operation of the latch device and adapted to bend when heated without fusing to operate the latch device heated without fusing to operate the latch device for releasing the body portion, and means for permanently electrically connecting one end of the bimetal thermostatic element with the contact element and permanently electrically connecting the other end of the bimetal thermostatic element with said member, so that the current passes through the thermostatic element upon a short circuit and upon an overload.

11. In a switch of the character described, a body portion, a contact element mounted upon the body portion, a resilient element to exert a force upon the body portion, a support, a member pivotally mounted upon the support and pivotally connected with the body portion, a lever pivotally mounted upon the body portion, a stop element mounted upon said member to engage with the lever, a bimetal thermo-trip element mounted upon the body portion and having a stop element to engage with said lever, and means electrically connecting the thermo-trip element with the contact element and said member.

12. In a switch of the character described, a body portion, a contact element mounted upon the body portion, a resilient element to exert a force upon the body portion tending to move the same to the open position, a support, a member pivotally mounted upon the support and pivotally connected with the body portion, a lever pivotally mounted upon the body portion to swing in a plane at substantially a right angle to the plane of movement of the member with relation to the body portion, said lever having a part provided with oppositely arranged beveled faces, a stop element mounted upon the member to engage with the beveled faces, a thermo-trip element which will bend when overheated mounted upon the body portion and having a stop element normally arranged in the path of travel of the lever, and means to electrically connect the thermo-trip element with the contact and said member.

13. In a switch of the character described, a body portion, a contact blade mounted upon the body portion, a pin carried by the body portion, a contact element to be engaged by the contact blade when the body portion is in the closed position, resilient means engaging the pin and urging the body portion toward the open position, a support, a member pivotally mounted upon the support and pivotally connected with the body portion, means to prevent the body portion from turning in one direction with relation to the member including a lever pivotally mounted upon the body portion, said lever being provided with a pair of oppositely arranged beveled faces, a stop element mounted upon said member to engage said beveled faces, a spring 70 to move the lever toward the holding position, a thermo-trip element adapted to bend when overheated mounted upon the body portion and having a stop element arranged in the path of travel of said lever, and means to electrically 75

connect the thermo-trip element with the contact blade and said member.

14. In a switch of the character described, a body portion having an engaging part and a contact blade, a stationary contact to engage and disengage the contact blade, resilient means engaging said engaging part and serving to urge the body portion toward the open position, a self-closing arc extinguishing device arranged adjacent to the stationary contact and closing when the contact blade is moved from the arc extinguishing device, a support, a member pivotally mounted upon the support and pivotally connected with the body portion, means to hold the body portion from turning in one direction upon its pivot with relation to said member including a pivoted lever, means including a thermo-trip element for controlling the movement of the lever, means for connecting the thermo-trip element with the contact blade, and means for connecting the thermo-trip element with said member.

15. In a switch of the character described, a housing having one side open, a stationary contact mounted within the housing, a self-closing arc extinguishing device arranged adjacent to the stationary contact and including a pair of oppositely arranged plates, a body portion, a door carrying the body portion and adapted to close the open side of the housing, a member pivotally mounted upon the housing and pivotally connected with the body portion, means to prevent the body portion from turning upon its pivot with relation to the member including a lever pivoted upon the body portion, means to control the movement of the lever including a thermo-trip element mounted upon the body portion, a contact blade mounted upon the body portion and movable between the plates of the 30 arc extinguishing device into engagement with the stationary contact, a resilient element having a socket, and a pin carried by the body portion to engage the resilient element and enter the socket.

45. In a switch of the character described, a housing, a pair of stationary contacts mounted within the housing, a guide arranged beneath and adjacent to the stationary contacts, reciprocal plates mounted within the guide and 50 adapted when closed to cover the contacts, springs to shift the plates to the closed position, a body portion, a contact blade mounted upon the body portion to pass between the plates and engage between the stationary contacts, spring means to move the body portion from the stationary contacts, a member pivotally mounted upon the housing and pivotally connected with the body portion, means to prevent the body portion from turning upon its pivot in one direction with relation to the member including a lever pivoted upon the body portion, means for controlling the movement of the lever including a thermo-trip element, means to connect the thermo-trip element with the contact blade, and means to connect the thermo-trip element with said member.

65. In a switch of the character described, a housing, a stationary contact arranged therein, a self-closing arc extinguishing device arranged upon one side of the contact, a body portion to be arranged within the housing, a contact blade carried by the body portion to be moved through the arc extinguishing device and to engage with the contact blade, a member pivotally mounted upon the housing and pivotally connected with

the body portion, means controlling the swinging movement of the body portion upon its pivot with relation to the member including a thermo-trip element, resilient means to shift the body portion from the stationary contact, means to electrically connect the thermo-trip element and contact blade, and a wire connected with the thermo-trip element and having connection with the pivoted member.

18. In a switch of the character described, a 10 housing, a conductor-bar mounted within the housing and having its ends arranged adjacent to the opposite sides of the housing, said ends having means for connection with a terminal connection, a stationary contact connected with the conductor-bar, a generally U-shaped conductor-bar mounted within the housing beneath the first named conductor-bar and provided at its ends with bearings, said U-shaped conductor-bar being provided in its sides with elements for engagement with a terminal connection, a body portion mounted within the housing, a contact blade mounted upon the body portion and arranged to engage with the stationary contact, a 15 member having pivot elements engaging in the bearings and pivotally connected with the body portion, means to control the swinging movement of the body portion upon its pivot in one direction with relation to the member including a pivoted lever, means to control the movement of the pivoted lever including a thermo-trip element, means to electrically connect the contact blade and thermo-trip element, a wire connected with the thermo-trip element and connected with 20 said member, and resilient means to move the body portion from the stationary contact.

19. In a switch of the character described, a body portion having an engaging part and a contact blade, a stationary contact to engage and disengage the contact blade, resilient means engaging said engaging part, a self-closing arc extinguishing device arranged adjacent to the stationary contact and closing when the contact blade is moved from the arc extinguishing device, a support, means pivotally connecting the body portion with the support, means to hold the body portion against swinging movement in one direction upon the pivot means, means including a 25 thermo-trip element for controlling the action

of the holding means, means for connecting the thermostatic element with the contact blade, and means for connecting the thermostatic element with the pivot means.

5 20. In a switch of the character described, a housing having one side open, a stationary contact mounted within the housing, a self-closing arc extinguishing device arranged adjacent to the stationary contact and including a pair of oppositely arranged plates, a body portion, a door carrying the body portion and adapted to close the open side of the housing, means for pivotally mounting the body portion upon the housing, means to prevent the body portion from turning in one direction upon the pivot means, means including a thermostatic element, a contact blade mounted upon the body portion and movable between the plates of the arc extinguishing device into engagement with the stationary contact, a resilient element, a part carried by the body portion to engage the resilient element, means to electrically connect the thermostatic element with the contact blade, and means to electrically connect the thermostatic element with the pivot means.

20 21. In a switch of the character described, a body portion, a contact element mounted upon the body portion, a coating contact element to engage the first named contact element, means to pivotally support the body portion so that it may move to an open position to break the engagement between the contact elements, releasable means to hold the body portion against turning movement in one direction upon the pivot means, a bimetal thermostatic element mounted upon the body portion to control the action of the releasable means and adapted to move when heated without fusing, means for permanently electrically connecting one end of the bimetal thermostatic element with the contact element carried by the body portion, and means for permanently electrically connecting the other end of the bimetal thermostatic element with the pivot means, the arrangement being such that the current passes through the bimetal thermostatic element upon a short circuit and upon an over-load.

AVERY L. SALTER.
